United States Patent Office

Des. 187,595
Patented Apr. 5, 1960

187,595

DESK OR THE LIKE

Robert I. Anderson, Muskegon, Mich., assignor to The Brunswick-Balke-Collender Company, Chicago, Ill., a corporation of Delaware

Application September 6, 1957, Serial No. 47,626

Term of patent 14 years

(Cl. D33—7)

Fig. 1 is a perspective view looking diagonally toward the rear of the desk or the like showing my new design;

Fig. 2 is a rear elevational view thereof;

Fig. 3 is a side elevational view thereof looking toward the left side of Fig. 2; and

Fig. 4 is a front elevational view thereof.

The dominant features of my design are shown in full lines.

I claim:

The ornamental design for a desk or the like, as shown and described.
